UNITED STATES PATENT OFFICE

2,599,735

STEAM GENERATOR

Basil Woynar, Chicago, Ill., assignor to Combustion Engineering-Superheater, Inc., a corporation of Delaware

Application January 27, 1948, Serial No. 4,580

1 Claim. (Cl. 122—282)

1

The present invention relates to heat exchange apparatus and particularly to a steam generator of the forced circulation type which is of high capacity and compact construction.

In trains hauled by either electric or diesel-electric locomotives it is necessary to provide as auxiliary equipment one or more steam generators to heat the cars of the train and for other purposes. The designers of diesel locomotives allocate only a small amount of space for the accommodation of steam generators and, accordingly, it is essential that they be of compact construction and of relatively high capacity. The limitations of space also make it difficult to obtain access to the steam generating elements in such installations when it is necessary to inspect or replace them.

In accordance with the present invention compactness of construction is obtained in part by utilizing forced circulation of water through the elements of the generator together with a novel arrangement of these elements which not only minimizes the space that they occupy but also facilitates the removal of a worn element from the generator when required without substantially disturbing other parts of a diesel motor installation.

The invention will be best understood upon consideration of the following detailed description of the illustrative embodiments thereof, when read in conjunction with the impending drawings.

Figure 1 is a sectional elevational view substantially on the lines 1—1 on Figs. 2 and 3 of a steam generator constructed in accordance with the present invention.

Figure 2 is a plan view;

Figure 3 is a sectional view on the correspondingly designated section line in Figure 1.

Referring first to Figure 1, the steam generator embodying the present invention has a U-shaped gas passage, one leg of which forms a furnace chamber 10 downwardly fired by fuel burner means 11 and communicating through its inner side wall at the lower end thereof with the adjacent convection passage 12 from the upper end of which the spent gases pass to a stack 13. As shown in Figures 1 and 3 the walls of the furnace chamber 10 are lined with radiantly heated steam generating surface comprising generally flat grid-like tube coils 14, 15, 16, and 17 each made up of a plurality of parallelly disposed pipe lengths disposed in contacting relation to form a water wall and interconnected at adjacent ends by integral return bends to provide for series flow through the tubes making up each coil, one of which is illustrated in Figure 6. As shown in

2

Figure 3 the right hand side of the furnace chamber 10 is semi-circular and accordingly the coils 14 and 15 are shaped to arcuate form in order to lie against the walls of the furnace.

5 The upper end portion 20 of the tube length 21 at one end of each coil 14-17 is connected to a water distributing header 22 which, as shown in Figures 2 and 3, is a tubular member bent to form a substantially complete loop extending around the periphery of the steam generator at its upper end. Thus, as shown in Figure 2 the water distributing header 22 runs around the three outer sides of both the furnace chamber 10 and convection passage 12 at the upper ends 10 thereof. The upper end portion 23 of the tube length 24 at the opposite end of each coil 14-17 is connected to a collecting header 25 which extends across the top of the steam generator in a position generally mid-way of the sides of the generator or substantially in the plane dividing the furnace chamber 10 and the convection passage 12.

20 To provide for the flow of gases from the furnace 10 into the convection passage 12 alternate tubes of the coils 16 and 17 that lie along the inner wall of the combustion chamber do not extend clear to the bottom of the furnace in order to provide an outlet opening 18 (Fig. 1) for gases to pass into the convection passage.

25 As shown in Figures 1 and 3 the steam generating surface in the convection passage 12 consists of several coil units 30, 31, 32 and 33 made up of tube lengths serially interconnected for fluid flow by return bends and having the constituent tubes 30 disposed in spaced relation in several parallel rows so that the tubes of the element are distributed among several parallel planes. From header 22 water enters the end portion 34 at the upper end of the initial tube in one of the rows 40 making up each element 30-33 and is discharged into collecting header 25 from the outlet portion 35 at the upper end of the tube forming a final part of the element and located at the opposite end of the last row of the several rows making up the element. The elements 30 to 33 receive water from the portion of supply header 22 that overlies the convection passage 12 and, like the radiant tubes 14 to 17, discharge into the centrally positioned collecting header 25. Transverse baffles 38 extending horizontally from opposite walls of passage 12 across the coils 30 to 33 deflect the gases so that they flow in a plurality of passes across the convection elements in their travel from the furnace chamber 10 to the stack 13.

The collecting header 25 discharges the mix-

ture of steam and water into the separator drum 40 from which the water flows through a down-comer 41 to the intake of the circulating pump 42 to be fed by the latter through the pipe 43 into the supply header 22. Thus, water taken from the separator drum 40 by the circulating pump 42 passes from the distributing header 22 in parallel through six radiantly heated circuits comprising the coils 14 to 17 lining the furnace walls, all of which coils discharge into the collecting header 25. The left end portion of the supply header 22 feeds the convection circuits comprising the four coils 30 to 33 inclusive whose tubes are disposed in the passage 12.

In the event it becomes necessary to remove any of the steam generating surface the detachment of stack 13 together with the end plates 50, 51 and 52 and the burner assembly 11 exposes the coils both in the furnace 10 and convection passage 12. Upon breaking the connection of collector header 25 with drum 40, the entire steam generating surface may be lifted out of the casing with headers 22, 25 and removed through a hatch 53 in the roof of the engine. If only a single radiant coil requires replacing it may be lifted out after cutting its end portions 20 and 23 from connection with the supply and collecting headers 22 and 25. In similar manner a convection coil 30 to 33 may be lifted out after the end portions 34 and 35 have been cut from the headers 22 and 25.

What I claim is:

In a steam generator; a generally rectangular casing including pairs of side and end walls disposed contiguously in upright relation between top and bottom closure walls; a tubular water supply header bent into a loop to extend along all of the exterior marginal edges of the upright side and end walls of said casing at its upper end; a collecting header mounted in a central posi-

tion within said loop confronting the end walls of the casing; steam generating tubes connected at their opposite ends directly into said headers and depending therefrom with the major portions of their lengths disposed in contacting relation in a row substantially beneath said collecting header to form a wall dividing the interior of said casing into a furnace combustion chamber and an adjacent gas passage; means for introducing fuel into said combustion chamber in a downward direction through the upper end wall of said casing, said tubes being arranged at their lower ends to provide an outlet disposed above but adjacent said bottom wall for gas flow from said furnace chamber into said gas passage; and other steam generating tubes connected at their ends directly into said headers and depending therefrom into said gas passage.
